UNITED STATES PATENT OFFICE

90,632

DESIGN FOR AN APPAREL BELT

Max Silverman, New York, N. Y.

Application June 3, 1933. Serial No. 48,267

Term of patent 3½ years

To all whom it may concern:

Be it known that I, MAX SILVERMAN, a citizen of the United States, residing at New York, county and State of New York, have invented a new, original, and ornamental Design for Apparel Belt, of which the following is a specification, reference being had to the accompanying drawing, forming part thereof and in which:

The figure is a perspective view of an apparel belt showing my new design.

I claim:

The ornamental design for an apparel belt, as shown.

MAX SILVERMAN.
